UNITED STATES PATENT OFFICE.

JOSEPH LEDERER, OF NEW YORK, N. Y.

INVERTED GAS-BURNER.

No. 917,774.

Specification of Letters Patent. Patented April 13, 1909.

Application filed July 1, 1907. Serial No. 381,806.

To all whom it may concern:

Be it known that I, JOSEPH LEDERER, a citizen of the United States, residing in the city, county, and State of New York, have 5 invented certain new and useful Improvements in Inverted Gas-Burners, of which the following is a specification.

This invention relates to inverted gas-burners of the Bunsen type and has for its 10 object the obtaining, in such a burner, of a superior mixture of gas and air to supply the Bunsen flame, of a superior, inverted, Bunsen flame of high intensity, and other advantages hereinafter described and pointed out in the 15 claims.

The invention is illustrated in the accompanying drawings which form part of this specification.

Figure 1 is an elevation, partly in vertical 20 section, of an inverted gas-burner made in accordance with this invention. Fig. 2 is an elevation of the inverted gas-burner shown in Fig. 1, with the globe, inverted mantle and gas-supply pipe removed. Fig. 3 is a plan 25 view from the top of the inverted gas-burner shown in Fig. 2, with the section above the line *a b* in Fig. 2, and the part below the globe holder, removed. Fig. 4 is an elevation, mostly in vertical section, of the gas- 30 check at the top of Fig. 2. Fig. 5 is a plan view from above of a horizontal section, except as to the plug *P*, of the gas-check shown in Fig. 4, made as indicated by the line *x y*. The arrows shown in Figs. 2 and 4 indicate, 35 respectively, the directions of the views shown in Figs. 3 and 5.

In the drawings like letters indicate like parts.

A is a gas-supply pipe, shown in Fig. 1 in 40 the shape of a goose-neck, but which may, however, be straight as well as curved or of any other suitable and convenient form or shape.

B is a gas-check for the regulation of the 45 supply of gas to the inverted, Bunsen gas-burner. The gas-check *B* may be of any suitable construction and it is, in any suitable manner, as by screw-threads, connected or joined with the gas-supply pipe *A* above 50 and the burner-tube or pipe *C* below.

C is the burner-tube or pipe of the inverted 55 gas-burner. The pipe *C* is suitably connected or joined, as by screw-threads, with the gas-check *B* above and the expansion cham-

its upper part, with perforations or air-inlet holes *E*.

D is an expansion chamber from which a pipe or tube *F* leads downwardly to the mouth or outlet *G* of the inverted gas-burner. 60

HH are projections or other suitable device, secured to the pipe or tube *F*, for attachment of the mantle support *I* provided with extensions *KK* suitable for engagement with the parts *HH*, from which support *I* the 65 inverted mantle *J* is suspended.

The burner-tube or pipe *C*, the expansion chamber *D* and the pipe or tube *F* constitute a channel for the passage of the gas and air mixture to the mouth of the inverted gas- 70 burner, and it is not necessary, for the purposes of this invention, that the said channel be composed of several parts or that it be of any special form or shape; nor is the expansion chamber *D* a necessary part of the chan- 75 nel.

Surrounding the channel for the downward passage of the gas and air mixture to the mouth *G* of the inverted gas-burner is a chamber *L* which may be of any suitable 80 form, preferably of the form of a cylinder provided with a dome-shaped top perforated to permit the gas-check *B* or channel for the downward passage of the gas and air mixture to enter the chamber *L*. Any suitable means 85 may be employed for closing the chamber *L* at the top and for this purpose the rim *M* about the perforation in the dome-shaped top of the chamber *L* may be secured and pressed between the top of the pipe or tube *C* and an 90 opposed projecting edge of the gas-check *B*, as shown in Fig. 1. The chamber *L* is provided, preferably at its lower part, with perforations *N*. The chamber *L* should be so 95 situated that it surrounds the perforations or air-inlet holes *E* in the channel for the downward passage of the gas and air mixture to the mouth *G* of the inverted gas-burner.

The lower end of the chamber *L* rests upon and is closed by a suitable base *O*, which is, 100 preferably, a slightly convex piece of metal surrounding the channel for the downward passage of the gas and air mixture. The base-piece *O* may be supported in any suitable manner, as by a nut *Q* screwed upon the 105 outer surface of the channel for the downward passage of the gas and air mixture which may be provided on its interior surface with screw-threads for such purpose. The base-piece *O* extends outwardly and, prefer-

110

ably, to the globe-holder R which it may support and with which it may be made in one piece. The base-piece O is provided on one side with one or more perforations S and is 5 otherwise closed. The parts of the base-piece O on the inner sides of the perforations S are, preferably, bent upwardly at an angle forming deflectors T. The base-piece O is referred to as a shield in the claims.

10 The chamber L and the base-piece O are so adjusted, one to the other, that the perforations N of the chamber L are situated above and near the closed part of the base-piece O and the closed part of the chamber L is situated 15 above and near the perforations S and the deflectors T of the base-piece O. In order to facilitate the described adjustment between the base-piece O and the chamber L, the chamber L should, preferably, be provided with notches U at its bottom, and the base-piece O with ridges or elevations V, the notches U and the ridges or elevations V being so shaped that the ridges or elevations fit closely into the notches. By means of the 20 nut Q the base-piece O may be pressed tightly against the bottom of the chamber L and the proper adjustment between the two may thereby be maintained. A globe W may be suspended from the globe-holder R.

25 From the foregoing description of the different parts of an inverted gas-burner, made in accordance with this invention, the function and mode of operation of the burner will readily be understood. Gas enters the gas- 30 supply pipe A and the flow of gas may be regulated, if desired, by the gas-check B. Upon reaching the air inlet holes E in the channel for the downward passage to the mouth G of the burner, the gas becomes 35 mixed with the air entering through the holes E and a mingling or mixing of the gas and air continues until the gas and air mixture issues from the mouth of the burner where it supplies the inverted Bunsen flame 40 which heats the inverted mantle J to incandescence.

45 The products of combustion, the result of the flame burning at the mouth G of the burner, rise in a heated condition and pass or escape through the perforation S in the base-piece O and are deflected from the chamber L by the deflectors T. The products of combustion do not, therefore, enter the chamber L through the perforations N. Pure air, the 50 oxygen of which has not been exhausted, as is the oxygen of the air which has mingled with the gas to form the Bunsen flame burning at the mouth G of the burner, enters the chamber L through the perforations N and 55 from the chamber L is drawn into the channel for the downward passage of the gas and air mixture through the perforations E. An efficient and proper supply of pure air, not exhausted of its oxygen, is, therefore, 60 65 cured in an inverted gas-burner made in ac-

cordance with this invention. Moreover, the parts above the inverted Bunsen flame become heated, including the chamber L, and by reason of the heated condition of the chamber L and its surrounding parts, the suction of air into the chamber L through the perforations N and into the channel for the downward passage of the gas and air mixture through the air-inlet holes E is considerably increased. Furthermore, the air in 70 passing through the heated chamber L becomes heated before entering the air-inlet holes E and mixing with the gas. The result is that in an inverted gas-burner, made in accordance with this invention, a superior 75 mixture of gas and air for the supply of the inverted Bunsen flame is obtained, because, among other reasons, the air employed for forming the gas and air mixture is pure air not exhausted of its oxygen, and is heated 80 air, and is air which, because of its heated condition, enters the chamber L and the air-inlet holes E at a higher rate of speed. Such a mixture of gas and air, containing a proper supply of oxygen, issues with greater 85 force or speed at the mouth G of the inverted burner and produces, in burning, a Bunsen flame of superior size and shape and of exceptionally high intensity, capable of raising 90 the inverted mantle to a high degree of incandescence.

Another advantage secured in an inverted burner made in accordance with this invention is the protection which is afforded to the gas-supply pipe A by the closed portion of 100 the base-piece O. In cases where the gas-supply pipe extends laterally, as does a goose-neck, the burner and the gas-supply pipe may be so adjusted that the gas-supply pipe will be situated above the closed portion 105 of the base-piece O and thus be protected against over heating by the rising, heated products of combustion.

A further advantage secured in an inverted burner, made in accordance with this invention, is the absence of any considerable amount of friction in the passage of the gas and air mixture from the air-inlet holes to the mouth of the burner, since the channel is, preferably, short and straight and the 110 friction which is encountered by the gas and air mixture in an inverted gas-burner provided, for example, with a long goose-neck tube having the air-inlet holes at the farther or lower end of the goose-neck is avoided. 115

120 It will be understood by those skilled in the art to which this invention appertains that variations may be made in details without departing from this invention.

What I claim is:—

1. In an inverted gas-burner, the combination of a chamber perforated on one side for the admission of air and a shield, below the chamber, provided with a horizontal part perforated on one side for the escape of 130

the products of combustion, the chamber and shield being so adjusted that the perforation of the chamber is turned away from the perforation of the shield, substantially as described.

2. In an inverted gas-burner, the combination of a chamber perforated on one side for the admission of air and a shield, below the chamber, provided with a horizontal

10 part perforated on one side for the escape of the products of combustion, the shield being provided with a deflector of the products of combustion at the place of its perforation and the chamber and shield being so adjusted that the perforation of the chamber is turned away from the perforation of the shield, substantially as described.

3. In an inverted gas-burner, the combination of a chamber perforated on one side 20 for the admission of air, a shield, below the chamber, provided with a horizontal part perforated on one side for the escape of the products of combustion, and a globe-holder supported by the shield, the chamber and shield being so adjusted that the perforation of the chamber is turned away from the perforation of the shield, substantially as described.

4. In an inverted gas-burner, the combination of a chamber perforated on one side for the admission of air and a shield, below the chamber, provided with a horizontal part perforated on one side for the escape of the products of combustion, the chamber and shield being provided with interlocking parts and the chamber and shield being so adjusted that the perforation of the chamber is turned away from the perforation of the shield, substantially as described.

40 5. In an inverted gas burner, the combination of a chamber perforated on one side for the admission of air and notched at the bottom and a shield, below the chamber, provided with a horizontal part perforated 45 on one side for the escape of the products of combustion and ridged upon its upper surface, the chamber and shield being so adjusted that the perforation of the chamber is turned away from the perforation of the shield and that each ridge of the shield fits into a notch of the chamber, substantially as described.

6. In an inverted gas-burner, the combination of a chamber perforated on one side 55 for the admission of air, a shield, below the chamber, provided with a horizontal part perforated on one side for the escape of the products of combustion and means for pressing the shield and the bottom of the chamber 60 closely together, the chamber and the shield being so adjusted that the perforation of the chamber is turned away from the perforation of the shield, substantially as described.

7. In an inverted gas-burner, the combination of a channel for the downward pas-

sage of gas and air, a chamber, perforated on one side for the admission of air, and a shield, below the chamber, provided with a horizontal part perforated on one side for the escape of the products of combustion, 70 the perforation of the chamber being turned away from the perforation of the shield, substantially as described.

8. In an inverted gas-burner, the combination of a channel for the downward passage 75 of gas and air, provided with air-inlet holes, a chamber surrounding the air-inlet holes of the channel and perforated on one side for the admission of air, and a shield, below the chamber, provided with a horizontal 80 part perforated on one side for the escape of the products of combustion, the perforation of the chamber being turned away from the perforation of the shield, substantially as described.

9. In an inverted gas-burner, the combination of a channel for the downward passage 85 of gas and air, provided with an expansion chamber, a chamber surrounding the channel and perforated on one side for the admission of air, and a shield below the chamber, provided with a horizontal part perforated on one side for the escape of the products of combustion, the perforation of the chamber being turned away from the perforation of 90 the shield, substantially as described.

10. In an inverted gas-burner, the combination of a channel for the downward passage 95 of gas and air, provided with air-inlet holes, a chamber surrounding the air-inlet holes of the channel and perforated on one side for the admission of air, a shield, below the chamber, provided with a horizontal part perforated on one side for the escape of the products of combustion, the chamber and shield being so 100 adjusted that the perforation of the chamber is turned away from the perforation of the shield, and an inverted mantle for incandescent gas-light, substantially as described.

11. In an inverted gas-burner, the combination of a gas-check, a channel for the downward passage of gas and air, a chamber perforated on one side for the admission of air, and a shield, below the chamber, provided with a horizontal part perforated on 110 one side for the escape of the products of combustion, the perforation of the chamber being turned away from the perforation of the shield, substantially as described.

12. In an inverted gas-burner, the combination of a gas-check, a channel for the downward passage of gas and air provided with air-inlet holes and with an expansion chamber, a chamber surrounding the air-inlet holes of the channel and perforated on 115 one side for the admission of air, and a shield, below the chamber, provided with a horizontal part perforated on one side for the escape of the products of combustion, the perforation of the chamber being turned away from the perforation of the shield, substantially as described.

away from the perforation of the shield, substantially as described.

13. In an inverted gas-burner, the combination of a channel for the downward passage of gas and air, provided with air-inlet holes, a chamber, surrounding the air-inlet holes of the channel, perforated on one side for the admission of air, a shield, below the chamber, provided with a horizontal part 10 perforated on one side for the escape of the products of combustion, and a globe-holder, the chamber and the shield being so adjusted that the perforation of the chamber is turned away from the perforation of the shield, substantially as described.

14. In an inverted gas-burner, the combination of a chamber perforated on one side for the admission of air, a shield, below the chamber, provided with a horizontal part 20 perforated on one side for the escape of the products of combustion, and a gas-supply pipe, the chamber and shield being so adjusted that the perforation of the chamber is

turned away from the perforation of the shield, and the gas-supply pipe and the 25 shield being so adjusted that the gas-supply pipe extends over the closed portion of the shield, substantially as described.

15. In an inverted gas-burner, the combination of a channel for the downward passage of gas and air, provided with air-inlet holes, a chamber surrounding the air-inlet holes of the channel and perforated on one side for the admission of air, and a shield, below the chamber, provided with a horizontal 30 part 35 perforated on one side for the escape of the products of combustion, the chamber and shield being so adjusted that the perforation of the chamber is turned away from the perforation of the shield, and the chamber being 40 so situated that it is above the flame of the burner, substantially as described.

JOSEPH LEDERER.
